UNITED STATES PATENT OFFICE

132,403

DESIGN FOR A DRESS

Philip Kaperst, New York, N. Y.

Application April 11, 1942, Serial No. 106,545

Term of patent 3½ years

To all whom it may concern:

Be it known that I, Philip Kaperst, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design,

Fig. 2 is a rear view of the dress shown in Fig. 1, and

Fig. 3 is an enlarged fragmentary view of Fig. 1 in unbuttoned position.

I claim:

The ornamental design for a dress, substantially as shown.

PHILIP KAPERST.
